US0D1109945S

(12) **United States Design Patent** (10) **Patent No.:** **US D1,109,945 S**
(45) **Date of Patent:** **** Jan. 20, 2026**

(54) **DRINKING TROUGH**

(71) Applicant: **SHENZHEN QIANHAI HOMERUN SMART TECHNOLOGY CO., LTD.**, Shenzhen (CN)

(72) Inventor: **Kun Liu**, Guangdong (CN)

(**) Term: **15 Years**

(21) Appl. No.: **35/523,895**

(22) Filed: **Dec. 31, 2024**

(80) **Hague Agreement Data**

Int. Filing Date: **Dec. 31, 2024**

Int. Reg. No.: **DM/243786**

Int. Reg. Date: **Dec. 31, 2024**

Int. Reg. Pub. Date: **Feb. 7, 2025**

(30) **Foreign Application Priority Data**

Jul. 4, 2024 (CN) 202430416380.1

Jul. 4, 2024 (CN) 202430416412.8

(51) **LOC (15) Cl.** **30-03**

(52) **U.S. Cl.**

USPC **D30/132**

(58) **Field of Classification Search**

Primary Examiner — Susan Moon Lee

(57) **CLAIM**

The ornamental design for a drinking trough as shown and described.

DESCRIPTION

1. Drinking trough
2. Drinking trough
Fig. 1.1 is a front elevation view of a drinking trough, in accordance with the present design;
Fig. 1.2 is a back elevation view thereof;
Fig. 1.3 is a left side elevation view thereof;
Fig. 1.4 is a right side elevation view thereof;
Fig. 1.5 is a bottom view thereof;
Fig. 1.6 is a top plan view thereof;
Fig. 1.7 is a perspective view thereof;
Fig. 2.1 is a front elevation view of a drinking trough, according to a second embodiment;
Fig. 2.2 is a back elevation view thereof;
Fig. 2.3 is a left side elevation view thereof;
FIG. 2.4 is a right side elevation view thereof;
fig. 2.5 is a bottom view thereof;
Fig. 2.6 is a top plan view thereof; and
Fig. 2.7 is a perspective view thereof.
The drinking trough is used to provide pets with drinking water.
